US0D1065876S

(12) **United States Design Patent** (10) **Patent No.:** **US D1,065,876 S**
(45) **Date of Patent:** **** Mar. 11, 2025**

(54) **MATTRESS COVER**

(71) Applicants: **Bruce M. Rippe**, Batesville, IN (US); **David John Ulrich**, Sunman, IN (US); **Misty Williams**, Osgood, IN (US); **Keith Michael Dye**, Versailles, IN (US); **Donna Denise Burdett**, Batesville, IN (US); **Harry Bryan Forwalt**, Holton, IN (US); **Judith Lynn Forwalt**, Holton, IN (US); **John David Miller**, Brookville, IN (US)

(72) Inventors: **Bruce M. Rippe**, Batesville, IN (US); **David John Ulrich**, Sunman, IN (US); **Misty Williams**, Osgood, IN (US); **Keith Michael Dye**, Versailles, IN (US); **Donna Denise Burdett**, Batesville, IN (US); **Harry Bryan Forwalt**, Holton, IN (US); **Judith Lynn Forwalt**, Holton, IN (US); **John David Miller**, Brookville, IN (US)

(73) Assignee: **Trinity Guardion, Inc.**, Batesville, IN (US)

(**) Term: **15 Years**

(21) Appl. No.: **29/932,632**

(22) Filed: **Mar. 14, 2024**

(51) LOC (15) Cl. **06-13**

(57) **CLAIM**

The ornamental design for a mattress cover, as shown and described.

DESCRIPTION

FIG. 1 is a top perspective view of the mattress cover; FIG. 2 is a front elevational view of the mattress cover of FIG. 1; FIG. 3 is a rear elevational view of the mattress cover of FIG. 1; FIG. 4 is a right side elevational view of the mattress cover of FIG. 1; FIG. 5 is a left side elevational view of the mattress cover of FIG. 1; FIG. 6 is a top plan view of the mattress cover of FIG. 1; FIG. 7 is a bottom plan view of the mattress cover of FIG. 1; FIG. 8 is a bottom perspective view of the mattress cover of FIG. 1; FIG. 9 is another bottom perspective view of the mattress cover of FIG. 1; and, FIG. 10 is a cross-sectional view of the mattress cover viewed along lines 10-10 in FIG. 4, and the cross section viewed from the opposite direction is identical in appearance. The broken lines represent portions and boundaries of the mattress cover that form no part of the claimed design.

1 Claim, 8 Drawing Sheets
